UNITED STATES PATENT OFFICE.

RAYMOND A. KIEFER, OF RAMSEY, NEW JERSEY.

DESIGN FOR A RECEPTACLE FOR GAS-VAPORIZERS.

46,402.

Specification for Design.

Patented Sept. 15, 1914.

Application filed July 23, 1914. Serial No. 852,687. Term of patent 14 years.

To all whom it may concern:

Be it known that I, RAYMOND A. KIEFER, a citizen of the United States, and a resident of Ramsey, in the county of Bergen and State of New Jersey, have invented a certain new, original, and ornamental Design for a Receptacle for Gas-Vaporizers, of which the following is a specification.

In the accompanying drawing, Figure 1 is a view in perspective of my newly de-

signed receptacle, and Fig. 2 a vertical sectional view thereof.

I claim:—

The ornamental design for a receptacle for gas vaporizers, substantially as shown.

RAYMOND A. KIEFER.
